US00D958102S

(12) **United States Design Patent** (10) **Patent No.:** **US D958,102 S**
Yu (45) **Date of Patent:** **** Jul. 19, 2022**

(54) **MOBILE PHONE**

(71) Applicant: **GUANGDONG OPPO MOBILE TELECOMMUNICATIONS CORP., LTD.**, Guangdong (CN)

(72) Inventor: **Sheng-Po Yu**, Guangdong (CN)

(73) Assignee: **GUANGDONG OPPO MOBILE TELECOMMUNICATIONS CORP., LTD.**, Dongguan (CN)

(**) Term: **15 Years**

(21) Appl. No.: **29/727,880**

(22) Filed: **Mar. 13, 2020**

(30) **Foreign Application Priority Data**

Sep. 20, 2019 (CN) 201930518173.6

(57) **CLAIM**

The ornamental design for a mobile phone, as shown and described.

DESCRIPTION

FIG. 1 is a front, right perspective view of a mobile phone, showing my new design;

FIG. 2 is a rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view of the portion 9 encircled in FIG. 2; and,

FIG. 10 is a partial enlarged view of the portion 10 encircled in FIG. 5.

The broken lines in FIGS. 2, 8, and 9 depict portions of the mobile phone that form no part of the claimed design.

The broken lines encircling a portion of the mobile phone in FIGS. 2, 5, 9, and 10 are included to show a partially enlarged view only and form no part of the claimed design.

1 Claim, 9 Drawing Sheets
